FLYING-MACHINE.

1,070,576.

Specification of Letters Patent. Patented Aug. 19, 1913.

Application filed May 4, 1911. Serial No. 625,015.

To all whom it may concern:

Be it known that I, FRANK M. BELL, a citizen of the United States, residing at El Paso, in the county of El Paso and State of Texas, have invented certain new and useful Improvements in Flying-Machines, of which the following is a specification.

This invention relates to flying machines of the type commonly known as "heavier than air" machines.

The object of the invention is to effect certain improvements in the construction of machines of this type with a view particularly to rendering such a machine more stable and facilitating the operation and control of the machine when in flight.

The invention involves numerous features of improvement in the construction of such machines and preferably these features are all used in combination in the same machine though certain of them may be used independently of the others as desired.

The invention is embodied preferably in a biplane and in this form of machine I provide a plurality of containers for gas in the upper of the two planes and locate the engine and other comparatively heavy portions of the apparatus upon or below the lower plane so that the center of gravity of the machine as a whole is low. In this way the stability of the machine when in flight is materially increased. In combination with this arrangement of the parts and disposition of the weight thereof, other means are provided for augmenting the stability of the machine both when moving horizontally through the air and when descending.

These and other features of the invention will be fully described hereinafter and definitely pointed out in the appended claims.

I wish it understood that the features of my invention are not limited to the type of machine above set forth having gas containers incorporated in the upper of two planes for certain of the features are of use in flying machines of various other types.

The preferred embodiment of my invention is illustrated in the accompanying drawings in which—

Figure 1 is a longitudinal section of the machine, Fig. 2 is a front view of the machine, Fig. 3 is a perspective view of one of the vertical fins, Fig. 4 is a view of a portion of one of the engines and certain parts associated therewith, Fig. 5 is a sectional view of certain of the controlling devices,

Fig. 6 is a detail view in section of one of the handles shown in Fig. 5, Fig. 7 is a top view of the engines and the horizontal propeller, Fig. 8 is a view illustrating the starting devices, Fig. 9 is a view of one of the adjustable weights and Fig. 10 is a sectional view of the machine with the operating mechanism removed, showing the arrangement of the openings through the planes.

Referring to these drawings, the machine illustrated is a biplane, the lower plane being indicated by the reference 1 and the upper plane by the reference 2. The upper plane has a plurality of containers for gas mounted therein, these containers being shown at 3. Preferably the several containers are individually removable so that one which has become partially or wholly deflated may be removed and a new one inserted in its place. The surfaces of the upper plane on either side of the gas containers 3 are formed of suitable material, such that substantially unyielding surfaces are presented to the air. The frame of the machine is extended downwardly below the lower plane as indicated at 4 and the two engines 5 and 6 are mounted upon this portion of the frame below the lower plane 1. Below the engines the frame 4 has wheels 7 thereon for supporting the machine when not in use. By reason of the construction of the machine as thus far explained, the center of gravity is very low, and, in addition to this, the gas in the containers in the upper plane exerts a lifting force. These features of the construction combine to make the machine very stable when in flight. The gas containers, as shown in Fig. 2 are of substantial size but it will be readily appreciated that the dimensions of these containers may be varied as desired and also that the area of the upper plane may be increased above that shown in the drawings, so as to secure a greater lifting effect of the gas in the containers associated with the upper plane.

In the lower plane 1 is a central opening which is of substantial size and the two engines 5 and 6 are mounted at opposite sides of this opening so that they do not obstruct passage of air upwardly through the opening between the two parts of the lower plane 1. The opening is shown on Figs. 2 and 10 at 78; it is of substantial width and extends from the front edge to the rear edge of the plane. Each of the two engines 5 and 6

drives a vertically disposed propeller, these being indicated by the references 8 and 9 respectively. These two propellers are mounted on concentric shafts, the propeller 9 being secured upon a hollow shaft 10 which turns on the shaft 11 carrying the propeller 8. Chains 12 gear the two shafts 10 and 11 to the engine shafts. In this way either engine may be driven alone or the 10 two engines may be driven simultaneously and at any desired speeds, and the propelling force exerted by the two propellers will not tend to turn the machine from a straight course.

15 One of the two engines is arranged to drive a horizontally disposed propeller 13 which is mounted for rotation upon the downward extension 4 of the frame of the machine and is in line with the opening 20 through the lower plane 1. The upper plane 2 has a central opening therethrough in line with the central opening through the plane 1; this opening is indicated by the reference 79 on Figs. 2 and 10 and is preferably of the same size and shape as the opening 78 in the lower plane. In this way the free passage of air through the center of the two planes is permitted and this is of advantage for several reasons. 25 30 When starting, the passage of air downwardly through the central openings to the starting propeller 13 is unobstructed. These central openings, however, are of greater importance in connection with the vertical fins hereinafter described for guarding against canting of the machine, particularly when descending. It will be noted also that the passage of air to and from the propellers 8 and 9 is not obstructed by the engines or by the planes as a result of which 35 40 increased speed is obtained with the same expenditure of power.

Mounted upon the frame of the machine in line with the central openings through the 45 planes is a vertical fin 14 which, in the preferred embodiment of the invention, is so arranged that it may be collapsed more or less to vary its effective area as desired. In the present instance this fin is shown as 50 projecting upwardly above the upper plane 2 when in its extended or operative position. Referring to Fig. 3 it will be seen that the fin 14 consists of flexible material secured to a plurality of supports 15 each of which 55 is pivotally mounted upon one of the members of the frame extending longitudinally of the frame, so that it may turn on its pivot in a plane fore and aft of the machine. The supports 15 extend below their pivots 60 and these lower ends are united by a bar 16. For raising or lowering the fin 14 cords or wires 17 are provided, these being secured to the opposite ends of the bar 16 and passing over suitable pulleys and down to a 65 handle 70 adjacent to the seat for the oper-

ator whereby they may be operated so as to move the bar 16 longitudinally and thereby rock the supports 15 on their pivots to raise or lower the fin 14. To assist in holding the fins against lateral movement, stays 82 70 may be provided extending from the upper end of the supports 15 down to the frame of the machine at points on the frame in line with the pivots of the respective supports transversely of the machine. In the present instance I have shown three such vertical fins, one mounted in line with the central opening through the planes of the machine and two others mounted in openings in the planes on opposite sides of and distant from the central opening. These two fins are indicated at 18. It will be seen that each of them is arranged vertically in an opening 80 through the upper plane 2 and that an opening 81 is provided in the lower plane 85 1 under that opening in plane 2. Preferably all three of the vertical fins shown are employed but I may utilize only the two fins 18 or only the one central fin 14. These vertical fins are of material assistance in maintaining the stability of the machine when in the air as the coaction of the air with the fins counteracts rocking movement of the machine. This function of the fins 14 and 18 is made much more effective by 90 the provision of the openings through the planes in alignment with the fins, since these openings allow the air to pass unobstructedly into coaction with the fins. The vertical fins are most useful when descending as it is then that rocking movement of 95 the machine is more apt to occur, for at such times it is usual to materially reduce the speed of the machine. During such descent air passes upwardly through the openings 100 in the planes quite freely and if the machine rocks slightly the planes act upon the air passing through the openings to resist further rocking movement. The mechanism shown for collapsing the fins so as to 105 vary the effective area thereof permits of folding the fins to an inoperative position when traveling in a substantially horizontal direction.

110 Each of the engines 5 and 6 is a gasoline engine of any suitable construction and is provided with a carburetor as shown at 19. Gasoline is supplied to these carburetors or directly to the engines from tanks 20 and these tanks are so mounted that they assist in maintaining the stability of the machine in the air. The tanks are mounted above the level of the carburetors or engines so that the gasoline will flow freely and they are mounted upon the lower plane 1 on opposite sides of the center thereof and distant from the center. The weight of these tanks and the liquid therein is, therefore, disposed far out from the center of the machine, and thus assists in maintaining 115 120 125 130

the equilibrium of the machine. I have also provided for automatically starting each of the gasoline engines by means of compressed air and this air is stored in tanks which are located in the lower part of the machine and serve as pontoons when the machine descends upon water. The tanks for the compressed air are shown at 21, there being two of these tanks one under each of the engines.

Referring to Fig. 8 air may be admitted from tank 21 through a pipe 22 controlled by a valve 23 to a compressed air motor 24 which is connected by a gear 25 to a toothed rim 26 (Fig. 4) encircling the fly-wheel 27 of the engine. The rim 26 is provided with a plurality of spring-pressed pawls 28 adapted to take into notches in the periphery of the fly-wheel 27. To start the engine it is only necessary to admit air to the motor 24 which will thus drive rim 26 and through the pawls 28 and fly-wheel 27, the engine shaft. As soon as the engine has become started in this way the fly-wheel 27 may rotate freely within the rim 26. Such a motor 24 is provided for each of the two engines. For compressing air within the tanks 21 air compressors 29 are provided arranged to be driven by the fly-wheels of the engines. For this purpose each compressor is mounted upon a lever 30 pivotally mounted upon the frame of the machine and this lever is connected by a rod 31 with a pedal 32 which may be depressed so as to rock lever 30 upon its pivot and thus carry the driving wheel of the compressor 29 into engagement with the fly-wheel of the engine. The air compressor 29 is connected by a pipe 33 with the tank 21. One of the engines, as for instance the engine 6, is provided with a reversing gear 34 operated by a lever adjacent to the operator's seat so that one of the propellers may be operated in the reverse direction when desired. One of the engines, as for instance engine 5, is connected to the horizontal propeller 13 so that it may be utilized for driving that propeller when desired as for instance when ascending. For this purpose a clutch member 35 is shown which may be moved by means of a yoke 36 into coaction with a clutch member 37 loose upon the shaft of the engine 5 and carrying the sprocket of one of the driving chains 12. The clutch member 35 may also be moved into coaction with another clutch-member secured to a friction disk 38 with which coacts a friction disk 39 splined upon a shaft 40 mounted for rotation upon the frame of the machine. The shaft 40 carries a gear 41 meshing with a gear 42 upon a vertically disposed shaft upon which the propeller 13 is secured. When it is desired to ascend, the clutch 35 is thrown to position for driving the propeller 13 by means

of the engine 5 and the other engine 6 is utilized for driving one of the vertically disposed propellers. After the desired altitude has been reached the engine 5 may be uncoupled from the propeller 13 and utilized for driving its vertically disposed propeller 8.

To assist in maintaining the equilibrium of the machine I provide weights adjustable longitudinally and transversely of the machine. The longitudinally adjustable weight is shown at 43 in Figs. 1 and 9, this weight being arranged to slide upon a rod 44 secured to the frame of the machine. A cord 45 is secured at its ends to the weight 43 and passes around pulleys at opposite ends of rod 44. This cord is wound two or more times upon a drum 46 which may be rotated by a handle 47 to vary the position of the weight 43. The rod 44 extends a substantial distance forward and rearward of the planes of the machine so that a substantial range of adjustment of the weight 43 is provided. The transversely adjustable weight is shown at 48 in Fig. 2 and its position may be adjusted in the manner described in connection with Fig. 9. The rod upon which this weight slides extends outwardly to the extreme ends of the planes so that the range of adjustment of this weight is also very wide. The transversely adjustable weight 48 is of particular utility in a machine of the type illustrated as one or more of the gas containers may become partially or wholly deflated so that the lifting power of the gas is unevenly distributed.

Referring to Fig. 5 it will be seen that a duplicate control-system is provided. Two seats for operators are shown at 49 and three or more concentric shafts 50 extend across these two seats. Each shaft is provided with two operating handles 51, one adjacent to each of the seats 49. Also each shaft 50 has a crank-arm 52 secured thereto from the lower end of which a rod connects with the part to be operated thereby. In the present instance I have shown three concentric shafts 50 and these are connected through the crank-arms 52 with the front control 53, rear control 54 and the rudder 55.

It is not desired to have the machine controlled from the two seats 49 simultaneously and I have, therefore, shown the handles 51 detachable from their respective shafts 50 so that either set of handles may be rendered operative or inoperative. For this purpose the several handles may be constructed as shown in Fig. 6. Each handle has a plunger 56 extending therethrough moved upwardly from the shaft by a spring 57. The plunger may be depressed by a button at its outer end to carry the opposite end into an opening in the shaft which is to be operated by the handle. When the plunger 56 is so moved it is held in operative position for driving the propeller 13 by means

tion by a spring-pressed latch 58 which engages a wall on the interior of the handle. To render the handle inoperative a transverse plunger 59 is depressed against the 5 tension of a spring coiled upon it so as to move the latch 58 out of coaction with the interior wall of the handle and thus allow spring 57 to move plunger 56 to the inoperative position.

10 I wish it understood that my invention, so far as it concerns the duplicate controlling mechanisms, is independent of the particular type of control system employed in the machine and the particular arrangement of the devices for operating the same. Thus, the use of a front control, as that shown at 53, and means for moving it is not essential, and the arrangement of the handles 51 may be varied as desired without 15 departing from the spirit of my invention, which contemplates broadly the use of two seats for operators, duplicate operating mechanisms, one operated from each of the seats, and means whereby either operating mechanism 20 may be rendered inoperative, so that the machine will be controlled only by the other operating mechanism.

Having now described my invention, what I claim as new therein and desire to secure 30 by Letters Patent is as follows:

1. A flying machine having a frame, a plane mounted thereon, a gas-engine mounted on the frame, a reservoir for compressed air, and connections from the reservoir to 35 the engine for starting the engine with air from the reservoir, said reservoir being located in the lower part of the machine and serving as a pontoon when the machine descends upon water, substantially as set forth.

40 2. A flying machine having a frame, a plane mounted thereon, a gas-engine mounted on the frame, a seat for an operator, controlling devices located adjacent thereto, a plurality of tanks constituting a reservoir, 45 an air compressor driven by the engine for compressing air in the reservoir, a motor, and means controlled by the operator for admitting air to the motor from the reservoir and connecting the motor in driving

50 relation to the engine, said tanks being located in the lower part of the machine and on opposite sides of the center thereof and serving as pontoons when the machine descends upon water, substantially as set forth.

55 3. A flying machine comprising the combination of a frame, a plane mounted thereon and having an opening therethrough at the center, a vertically-disposed fin mounted upon the frame in line with said opening, 60 a horizontally-disposed propeller mounted for rotation in line with said opening, and an engine for driving the propeller, substantially as set forth.

4. A flying machine comprising the combination of a frame, a plane mounted there-

on and having an opening therethrough at the center, a vertically-disposed fin mounted upon the frame in line with said opening, means for varying the effective area of the fin, a horizontally-disposed propeller mounted for rotation in line with said opening, and an engine for driving the propeller, substantially as set forth. 70

5. A flying machine comprising the combination of a frame, a plane mounted thereon and having an opening therethrough at the center, a vertically-disposed fin mounted upon the frame in line with said opening, a horizontally-disposed propeller mounted for rotation in line with said opening, two engines mounted on opposite sides of the opening, and means for driving said propeller from one of said engines, substantially as set forth. 75

6. A flying machine comprising the combination of a frame, two planes mounted thereon one above the other and both having openings therethrough at the center, a plurality of gas-containers mounted upon the upper plane, two engines mounted upon the frame below the lower plane and on opposite sides of said opening, a horizontally-disposed propeller mounted for rotation in line with said opening, means for driving the propeller, a vertically-disposed fin mounted in line with said openings, and means for varying the effective area of said fin, substantially as set forth. 80

7. A flying machine comprising the combination of a frame, a plane mounted thereon having openings therethrough on opposite sides of the center of the machine, a vertically-disposed fin in line with each of said openings, and an engine for propelling the machine, substantially as set forth. 90

8. A flying machine comprising the combination of a frame, a plane mounted thereon having openings therethrough on opposite sides of the center of the machine, a vertically-disposed fin in line with each of said openings, means for varying the effective area of said fins, and an engine for propelling the machine, substantially as set forth. 100

9. A flying machine comprising the combination of a frame, two planes mounted thereon one above the other and having aligned openings therethrough on opposite sides of the center, vertical fins disposed in line with said openings, means for varying the effective size of said fins, gas-containers mounted in the upper plane, a gas-engine mounted on the frame below the lower plane, and a propeller driven by the engine, substantially as set forth. 110

10. A flying machine comprising the combination of a frame, a plane mounted thereon and having a central opening therethrough and openings on opposite sides of the center, a vertically-disposed fin mounted 120

in line with each of said openings, means 5 for varying the effective area of said fins, a horizontally-disposed propeller rotating in line with the central opening, a vertically-disposed propeller, and means for driving the propellers, substantially as set forth.

11. A flying machine comprising the combination of a frame, a plane, an engine 10 mounted on the frame, a propeller driven thereby, controlling mechanism, two seats for operators mounted on the frame, means for operating said controlling mechanism from either of said seats, and means for 15 rendering said operating means either operative or inoperative, substantially as set forth.

12. A flying machine comprising the combination of a frame, two planes mounted 20 thereon one above the other, two gas engines mounted upon the frame, two independently rotatable, vertically-disposed, concentric propellers, gearing connecting each 25 of the engines to one of the propellers, a weight, means for adjusting the position of

the weight lengthwise of the machine, said weight being capable of movement a substantial distance forward or rearward of said planes, a second weight and means for moving said second weight transversely of 30 the machine to any position between the ends of the planes, substantially as set forth.

13. A flying-machine comprising the combination of a frame, a plane mounted thereon, an engine mounted on the frame, a propeller driven by the engine, two seats for operators mounted on the frame, controlling mechanism, two sets of operating devices for said controlling mechanism, one set mounted adjacent to each of said seats, and 35 means for rendering either of said sets of operating devices operative or inoperative, substantially as set forth.

This specification signed and witnessed this 20th day of April, 1911.
